US0D1053196S

(12) **United States Design Patent** (10) Patent No.: **US D1,053,196 S**
(45) Date of Patent: ** Dec. 3, 2024

(54) **DISPLAY SCREEN WITH STAND**

(71) Applicant: **LG ELECTRONICS INC.**, Seoul (KR)

(72) Inventors: **Woosuk Park**, Seoul (KR); **Hyojin Won**, Seoul (KR); **Seunghyeop Lee**, Seoul (KR)

(73) Assignee: **LG ELECTRONICS INC.**, Seoul (KR)

(**) Term: **15 Years**

(21) Appl. No.: **35/519,181**

(22) Filed: **Nov. 28, 2022**

(80) **Hague Agreement Data**

Int. Filing Date: **Nov. 28, 2022**

Int. Reg. No.: **DM/227140**

Int. Reg. Date: **Nov. 28, 2022**

Int. Reg. Pub. Date: **Dec. 1, 2023**

(30) **Foreign Application Priority Data**

Jun. 23, 2022 (KR) 30-2022-0025086

(51) **LOC (14) Cl.** **14-06**

(52) **U.S. Cl.**

USPC **D14/452**

(58) **Field of Classification Search**

(57) **CLAIM**

The ornamental design for a display screen with stand as shown and described.

DESCRIPTION

- 1.1 : Perspective view of a first position
- 1.2 : Rear perspective view thereof
- 1.3 : Front elevation view thereof
- 1.4 : Rear elevation view thereof
- 1.5: Left side elevation view thereof, the right side view omitted because it is symmetrical to the left side view
- 1.6: Top plan view thereof
- 1.7 : Bottom plan view thereof
- 1.8 : Rear perspective view in a detached state
- 1.9 : Rear perspective view of a second position
- 1.10 : Front Perspective view thereof
- 1.11 : Rear perspective view thereof
- 1.12 : Front elevation view thereof
- 1.13 : Rear elevation view thereof
- 1.14: Left side elevation view thereof, the right side view omitted because it is symmetrical to the left side view
- 1.15: Top plan view thereof
- 1.16 : Bottom plan view thereof
- 1.17 : Rear left perspective view of a third position
- 1.18 : Rear right perspective view thereof

(Continued)

1.19 : Front elevation view thereof
 1.20 : Rear elevation view thereof
 1.21 : Left side elevation view thereof
 1.22 : Right side view thereof
 1.23 : Top plan view thereof
 1.24 : Bottom plan view thereof
 1.25 : Perspective view of a fourth position
 1.26 : Rear perspective view thereof
 1.27 : Front elevation view thereof
 1.28 : Rear elevation view thereof
 1.29 : Left side elevation view thereof
 1.30 : Right side elevation view thereof
 1.31 : Top plan view thereof
 1.32 : Bottom plan view thereof
 1.33 : Perspective view of a fifth position
 1.34 : Rear perspective view thereof
 1.35 : Front elevation view thereof
 1.36 : Rear elevation view thereof
 1.37 : Left side elevation view thereof, the right side view omitted because it is symmetrical to the left side view
 1.38 : Top plan view thereof
 1.39 : Bottom plan view thereof
 The evenly spaced broken lines that are immediately adjacent to the claim, and encompass additional broken lines, depict the bounds of the claimed design, while all other broken lines are directed to environment. The broken lines form no part of the claimed design.

1 Claim, 39 Drawing Sheets
